UNITED STATES PATENT OFFICE.

GEORGE HERBERT SCOTT, OF BECKENHAM, ENGLAND.

MOORING GEAR FOR AIRSHIPS.

Application filed August 22, 1921. Serial No. 494,168.

To all whom it may concern:

Be it known that I, GEORGE HERBERT SCOTT, a subject of the King of Great Britain, residing in Beckenham, Kent, England, 5 have invented certain new and useful Improvements in Mooring Gears for Airships, of which the following is a specification.

This invention relates to improvements in mooring mast gear for airships of the type 10 wherein the fitting on the bow of the ship is coupled, with the aid of a mast wire or the like, to a fitting carried at the masthead, as for example at the upper end of an uprising lever mounted on the masthead with facility 15 of limited listing movement in any direction about a neutral point under the restraining action of resilient means or of the tension of the mast wire or mooring cable, as described in the specification of my application for 20 British Letters Patent No. 2652 dated 20th January 1921.

According to the present invention, the mooring gear comprises a mast which may be but is not necessarily of the type aforesaid, combined with means for anchoring side guys attached to the bow of the ship to the ground at any selected pair of points, respectively on the port and starboard sides of the ship. The anchor points are arranged 30 as a series usually but not necessarily equi-spaced apart and from and lying around the mast as a centre in different directions from it. The mooring gear also comprises means for hauling the ship down by the guys so 35 that their length between the ship's bow and the selected anchor points to which they are connected is equal to the distance from the coupling on the upper end of the mast lever to the selected anchor points. When the 40 mast wire is hauled in to engage the couplings on the ship's bow and the mast lever, the side guys steady the ship's bow against lateral hunting movement.

The side guys are attached to the nose of 45 the ship as near as convenient to the point to which the ship landing wire is attached.

The invention is illustrated in one form in plan and elevation respectively in Figs. 1 and 2 of the accompanying drawings. As 50 therein shown the means for anchoring the ship's side guys 9 to the ground comprise a number of fixed anchor points 3 arranged around the circle with the mast A as a centre, or they may comprise a circular rail or 55 track with the mast as a centre and two trolleys or the like adapted to be moved

round the track and anchored anywhere thereon. A convenient radial distance for the anchor points or track is, say, 500 feet. A winch 5 with two barrels (or two separate 60 winches) is placed at or near the foot of the mast, and ground wires 2 pass from the barrels, over leading blocks 4, if necessary, to any two selected anchor points or to the two 65 trolleys. At the anchor points or on the trolleys leading or snatch blocks are secured through which the ground wires are rove.

Assuming that the ship 6 is approaching the mast from any direction in light trim at some distance above it, the landing wire 1 70 on the ship's bow is first connected with the mast wire 8 in a customary manner, as by shackles indicated by the numeral 7, and the ship is allowed to ride up on the single wire. The two side guys 9 are now let down from 75 the nose of the ship, and the mast wire 8 is hauled in until these touch the ground. The ground wires 2 are then led from the winch or winches through the suitably placed leading blocks 4 near thereto and at the selected 80 anchor points or on the two trolleys, and the ends of the ground wires are brought together at the points on the ground, where the lower ends of the side guys 9 are resting, 85 and are attached to the latter, as by shackles 7.

The two anchor points used are chosen in, or moved to such positions on the leeward side of the mast as indicated in Fig. 1, that lines joining them to the foot of the mast make preferably an obtuse angle of, say, 90 120°, with each other, and also in such position that the direction of the wind approximately bisects such angle.

The side guys are then hauled in by the 95 winch barrels, while the mast wire is similarly hauled in until the length of the side guys between the ship's nose and the two selected anchor points or trolleys is equal to the distance from the coupling on the upper end of the mast lever to such anchor 100 points, as aforesaid.

The mast wire is then hauled in further until the couplings on the nose of the ship and on the mast lever become engaged, while the side guys locate the nose of the ship, and constrain it to move in the arc of a circle in a vertical plane passing through the mast lever coupling and about the horizontal axis constituting the base-line joining the two anchor points.

The vertical line passing through the nose 110 of the ship at the time of joining the ground

wire ends 2 to the lower ends of the ship's side guys 9, should be leeward of the base-line joining the two selected anchor points, while such vertical line, when the hauling in 5 of the side guys is complete, should be to windward of said base-line.

Having thus fully described the nature of the said invention and the best means I know for carrying the same into practical 10 effect, what I claim is:—

1. Mooring gear for airships comprising in combination with a mooring mast and bow mooring gear cooperating therewith, anchor points on the ground level equidistant from the mast, mooring lines attached 15

to the bow of the airship, and passing around said anchor points to securing means, and means for hauling in said mooring lines, substantially as described.

2. Mooring gear for airships according to 20 claim 1, wherein means are provided for positioning two anchor points substantially equidistant from the direction of the wind, on either side thereof, substantially as described.

25 In testimony whereof I have signed my name to this specification.

GEORGE HERBERT SCOTT.
